US00D877891S

(12) **United States Design Patent** (10) **Patent No.:** **US D877,891 S**
(45) **Date of Patent:** **** Mar. 10, 2020**

(54) **RECONSTITUTION AND DELIVERY DEVICE**

(71) Applicants: **Guangzhou Bioseal Biotech Co., Ltd.**, Guangzhou Science (CN); **Ethicon, Inc.**, Somerville, NJ (US)

(72) Inventors: **Shiwei Xie**, Foshan (CN); **Michael J. Trezza, II**, Long Valley, NJ (US); **John Goodman**, Ann Arbor, MI (US); **Jared Schneider**, Raritan, NJ (US)

(73) Assignees: **Guangzhou Bioseal Biotech Co., Ltd.**, Guangzhou Science City (CN); **Ethicon, Inc.**, Somerville, NJ (US)

(**) Term: **15 Years**

(21) Appl. No.: **29/644,657**

(22) Filed: **Jun. 6, 2018**

Related U.S. Application Data

(63) Continuation of application No. 29/549,431, filed on Dec. 22, 2015, now abandoned.

(51) **LOC (12) Cl.** **24-02**
U.S. Cl.

USPC **D24/112**

Primary Examiner — Nathan M Johnston

(74) *Attorney, Agent, or Firm* — David R. Crichton

(57) **CLAIM**

The ornamental design for a reconstitution and delivery device, as shown and described.

DESCRIPTION

FIG. 1 is a perspective view of a reconstitution and delivery device, showing our new design;

FIG. 2 is a top plan view thereof;

FIG. 3 is a side elevation view thereof;

FIG. 4 is a bottom plan view thereof;

FIG. 5 is a front elevation view thereof;

FIG. 6 is a rear elevation view thereof; and,

FIG. 7 is a perspective view of the reconstitution device shown in FIG. 1 in a standing position.

The broken lines show portions of the design that form no part of the claimed design

1 Claim, 6 Drawing Sheets
